United States Patent Office.

HENRY W. HOLCOMB, OF NORTHLAKE, MICHIGAN, ASSIGNOR TO HIMSELF AND W. FRANK HUGHES, OF SAME PLACE.

Letters Patent No. 96,917, dated November 16, 1869.

IMPROVEMENT IN HORSE-RAKES.

The Schedule referred to in these Letters Patent and making part of the same.

To all whom it may concern:

Be it known that I, HENRY W. HOLCOMB, of Northville, in the county of Wayne, and in the State of Michigan, have invented certain new and useful Improvements in Hay-Rakes; and do hereby declare that the following is a full, clear, and exact description thereof, reference being had to the accompanying drawings, and to the letters of reference marked thereon, making a part of this specification.

The nature of my invention consists in the construction and general arrangement of a horse hay-rake, as will be hereinafter fully set forth.

In order to enable others skilled in the art to which my invention appertains, to make and use the same, I will now proceed to describe its construction and operation, referring to the annexed drawings, in which—

Figure 1 is a plan view, and

Figure 2, a transverse vertical section of the rake.

Figure 3 is a rear view of a portion of the rake, showing the manner of holding the teeth down.

Figure 4 shows the mode of hinging or attaching the teeth.

A represents a bar, of suitable dimensions, having a journal at each end, on which the wheels B are placed.

Another bar, C, runs parallel with and in front of the bar or axle A, and connected with the same by means of the cross-pieces D D, fastened by bolts, or other suitable means.

On the upper side of the bar C, at regular intervals, are placed metal plates, a a, each having two ears on its upper side.

Through all these ears a rod, b, is run, as seen in fig. 1, and the inner ends of the rake-teeth I I are placed one on each plate, a, between its ears, under the rod, and then bent over the same, thus hinging all the teeth by or on one rod.

The teeth I extend over and rest on the axle A, and are held down on the same in the following manner:

On each side of the tooth is placed a pin, i, the upper end of which is secured in a bar, E, running parallel with and above the axle A, while the lower ends of said pins are inserted into holes in the axle A, which holes pass clear through the axle, so as to prevent any water from collecting into the same.

Around each pin is a coiled or spiral spring, e, the upper ends of which support the bar E, while the lower ends press on a plate, f.

This plate bears on the tooth, and is of such size that the two pins, one on each side of the tooth, pass through its ends, and thus two springs act on said plate, holding the tooth down on the axle A.

It will be seen that each tooth is provided with two pins i i, two springs e e, and one plate f.

The pressure of the springs e e on the teeth I I, and consequently the spring of the teeth may be regulated by moving the bar E up and down, and this is accomplished by letting one of the pins i at each end and one in the centre pass through the bar E, and providing these pins on top of said bar with set-screws h h.

By this means, the bar E can be raised or lowered at will, and consequently the force of the springs e e on the plates f be readily regulated.

On the rear side of the axle A are secured two upright metal bars F F, which extend up above the bar E, and are secured to the same by a screw or bolt passing through an elongated slot in the bar F, as seen in fig. 3.

The object of these elongated slots is to allow for the raising and lowering of the bar E.

To the upper ends of the bars F F, the shafts G G are hinged, said shafts extending so far to the rear that when the rake is turned for unloading they will rest on the axle A.

On the front side of the bar C is secured a spring latch, H, which catches on a cross-bar, J, which connects and braces the shafts G G together, thus holding the rake in proper position for work.

The driver's seat is placed over the axle on the shafts in such a position that he can readily release the latch with his foot, when the rake will turn up and unload the hay.

By means of a lever, K, attached to the axle A and the bar E, the driver can readily place it again in position for work.

Having thus fully described my invention,

What I claim as new, and desire to secure by Letters Patent, is—

1. The arrangement of the cross-bar C, parallel with and in front of the axle A, provided with the plates a and the single rod b, to which are hinged all the rake-teeth I, which are extended over the axle A and kept in position by the plates f and rods i i, and springs e e, all substantially as set forth.

2. The combination of the axle A, bar E, adjustable plates F, pins i i, springs e e, plates f, teeth I, bar C, catch H, and shafts G G, all constructed and operating substantially as herein set forth.

3. The spring latch H, when attached to the rake, in the manner and for the purposes herein set forth.

In testimony that I claim the foregoing, I have hereunto set my hand, this 13th day of August, 1869.

HENRY W. HOLCOMB.
